Primary Examiner—Holly Baynham**[57] CLAIM**

The ornamental design for the ultrasound transducer probe holder, as shown.

DESCRIPTION

FIG. 1 is a perspective view of an ultrasound transducer probe holder embodiment of this invention;

FIG. 2 is a side view of the ultrasound transducer holder of FIG. 1;

FIG. 3 is an adjacent side view of the ultrasound transducer probe holder of FIG. 1;

FIG. 4 is a side view opposite the side shown in FIG. 2;
FIG. 5 is a side view opposite the side shown in FIG. 3;
FIG. 6 is a top view of the ultrasound transducer probe holder of FIG. 1; and,

FIG. 7 is a bottom view of the ultrasound transducer probe holder of FIG. 1.
